UNITED STATES PATENT OFFICE.

DMITRY TROUBTSCHANINOFF, OF NEW YORK, N. Y.

SUBMARINE MINE.

1,302,732.

Specification of Letters Patent.

Patented May 6, 1919.

Application filed April 15, 1918. Serial No. 228,646.

To all whom it may concern:

Be it known that I, DMITRY TROUBTSCHANINOFF, a citizen of Russia, and residing at New York, county of New York, and 5 State of New York, have invented certain new and useful Improvements in Submarine Mines, of which the following is a specification.

The present invention relates to improvements in sub-marine mines and has for its particular object to provide means whereby it will be impossible to dislodge or remove such a mine, by cutting the cable connecting it with its anchor, without causing explosion thereof.

With the constructions heretofore employed the mines are frequently rendered harmless, or at least caused to rise to the surface and there exploded without accomplishing the purpose for which they were designed, by cutting the cables connecting the mines and anchors, or by engaging such cables with drags or similar devices operated by boats so as to draw the mine to the surface.

The present invention provides means whereby when the mine is disconnected from its anchor the explosive charge will be automatically separated from the buoyant body and exploded. More specifically the invention provides means whereby if the cable connecting the mine and anchor is severed by a sub-marine the explosive charge will be liberated from the buoyant casing and caused to explode at the depth at which the sub-marine is operating.

While the invention may be applied to mines of various forms and different types and there can of course be considerable departure from the exact embodiments thereof hereinafter referred to, the accompanying drawings illustrate two forms.

Referring to the drawings:

Figure 1 is a vertical section through a "contact" mine having one embodiment of the invention applied thereto;

Fig. 2 is a plan;

Fig. 3 is a view, of the same character as Fig. 1, of a portion of the mine, on a plane 50 at right angles to the section of Fig. 1;

Fig. 4 is an elevation and partial section of a slightly different form of mine and modification of the invention;

Fig. 5 is a different elevation of the same structure as is shown in Fig. 4;

55

Fig. 6 is a diagram of an electric circuit that may be employed;

Fig. 7 is a detail, sectional view of one of the external contacts;

Fig. 8 is a sectional, detail view of a form 60 of hydrostatic control device that may be employed with the embodiment of the invention illustrated in Figs. 4 and 5.

In the drawings many of the parts of the mine, which may be of any ordinary construction, are illustrated more or less diagrammatically.

In the form of the invention illustrated in Figs. 1 to 3, the mine comprises a buoyant body or casing 1, which is provided with an interior chamber or compartment 2, open at its lower end, within which is supported the explosive charge, the casing or holder for which is indicated at 3.

The mine is provided with a plurality of 75 outwardly projecting contact members 4. The construction and operation of these "contacts" does not constitute a part of the present invention but they are to be of the character commonly employed. As shown 80 in Fig. 7 each "contact" comprises a suitable receptacle containing positive and negative battery elements, 50, 51, and a frangible vessel 52 containing a liquid adapted when brought into contact with the elements 50, 85 51, to provide a source of electric current. The vessel 52 is shown as being surrounded by a deformable covering, 53, for example of lead. When any of said members 4 is broken an electric 90 circuit, including a suitable primer charge 60 in the body of explosive in the casing 3, is completed, igniting the primer and consequently exploding the mine. The conductors included in the circuits connecting said 95 primer charge with the several "contacts" 4 are indicated in dotted lines in Fig. 2 and conventionally illustrated at 5, 6, (Fig. 1) where they pass from the buoyant chamber of the body to the interior explosive contain-

100 ing chamber and in the diagram (Fig. 6). At its upper end the casing 3 for the explosive charge is provided with upwardly projecting brackets 7 one of which is engaged by the toe of a lever 8 which is suitably 105 fulcrumed on a lug or lugs depending from

- the removable cover plate 9 of the compartment 2; and the upper end of the anchor cable 10, is connected to the other arm of said lever so that the tension due to the weight of the anchor 10^a and cable and the tendency of the casing 1 to rise acts constantly to maintain the lever in engagement with the bracket 7 and thus support the explosive charge container within the compartment 2.
- 10 It will be seen that if the cable 10 is severed, or the anchor detached therefrom the strain on the lever 8 will be relaxed and as the buoyant body rises the casing 3 containing the explosive charge will escape through the lower open end of the compartment. In order that this relative movement of the body and explosive charge may not be materially hindered by the conductors of the explosion circuits hereinbefore referred to a knife like blade 11 may be arranged within the compartment 2 in position to sever said conductors, between the points 5 and 6, as the explosive charge and buoyant casing are disengaged.
- 15 Within the upper portion of the casing 3 is arranged a device 12, similar to the external "contacts" 4 including a frangible tube or liquid container and battery elements which are properly connected in circuit with the primer charge of the mine. A lever 13 fulcrumed within the casing 3 has one arm normally engaging a wire 14, that extends down from the aforesaid cover plate 9, and the other arm of said lever is adapted to break the frangible member of the device 12 and permit the liquid contained therein to escape and come into contact with the battery elements, as said lever is rocked by the downward movement of the casing 3.
- 20 The wire 14 extends through a slot in the arm of the lever 13 and has at its lower end an enlargement that prevents it from moving freely through the slot as the casing 3 descends relative to the casing 1. Therefore the wire 14 exerts an upward pull on the lever, causing it to turn on its pivot. The slot in the lever extends through the end of the arm in which it is formed and as the latter is rocked, the wire will escape from engagement with the lever permitting the casing 3 to pass freely from the buoyant body. Prior to placing the mine in the water the lever 13 may be retained in inoperative position by a stop rod 13^a extending through a suitable passage in the top and into a socket in the upper end of the lever.
- 25 Included in the electrical circuit (shown in Fig. 6) with the device 12 and the primer charge 60 are two terminals 15, 16, the one 15, being relatively stationary and the other movable away from and toward said stationary terminal. Normally the terminals 15, 16, are separated to such an extent that the electric circuit including the device 12 and the primer charge 60 will not be com-

pleted to cause ignition or explosion of said primary charge instantly on the lever 13 breaking the member 12. Means are provided whereby the terminal 16 will be held sufficiently far from the terminal 15 to prevent ignition of the primer charge until the casing 3 has entirely escaped from the buoyant body of the mine and reached approximately the depth at which the cable connecting the mine and anchor has been 75 broken.

Such means include a lever 17 which is fulcrumed on a stud rising from the upper end of the casing 3, and has one end extending into engagement with a rod or carrier 80 to the lower end of which the terminal 16 is connected. The other end of said lever 17 is provided with a roller 18 which bears against the cable 10. A spring 19 acts constantly to move the terminal 16 toward the 85 terminal 15, and to maintain the roller 18 in close contact with the cable 10, the pressure exerted by said roller 18 on the cable being resisted by a diametrically oppositely arranged roller 20. The upper end of the terminal 90 support is also connected with a diaphragm 16^a exposed to the pressure of the water in which the mine is submerged. The diaphragm 16^a is not directly exposed to contact with the water but as shown is clamped 95 between the members of a piston-like head 16^b that is exposed to such pressure and connected with the lever 17. The cable 10 extends throughout the length of the casing 3 passing through a centrally arranged tubular guide 21 and it will be seen that so long as said cable is between the rollers 18 and 20, the terminals 15 and 16 will be maintained separated to the maximum extent. As soon as the severed end of the cable 10 100 passes between the rollers 20 and 18 the spring 19 and the pressure of the water on the diaphragm at the upper end of the terminal support will move the terminal 16 sufficiently close to the terminal 15 to complete the electric circuit required for detonating the explosive charge. Therefore the explosion will occur at a depth which is close to that at which the cable 10 has been cut, and if the cutting was effected by a submarine the latter will be within range of the explosion and probably seriously damaged if not destroyed.

As hereinbefore stated the invention may be readily applied to mines of different types 120 and it is not necessary that the explosive charge be contained within the buoyant body.

In Figs. 4 and 5 there is illustrated, more or less diagrammatically, a mine comprising 125 an upper buoyant section 31 and a lower explosive containing section 32. The two sections are connected by projections 33 on the section 32 extending through eyes 34 on the upper buoyant section and by a hydro- 130

statically controlled means 35. With such a construction if the anchor cable is broken the entire mine will rise and when such rising has sufficiently reduced the hydro-static pressure on the connection 35 the latter will be disengaged and the lower, explosive containing, section 32 will swing downwardly, about the engagement of the projection 33 and eyes 34 as an axis, until said projections can escape from the eyes 34, when the two sections of the mine will be entirely disconnected.

In this embodiment of the invention the frangible member of the device 12^a controlling the electric circuit for detonating the explosive charge is broken, during the turning movement of the section 32, by contact with a member 62 carried by the buoyant section 31. The means for preventing premature explosion, or deferring such explosion until the charge has reached the desired depth, is the same in this form of the invention as in that previously described.

The anchor cable 10 extends through a suitable central passage in the lower section 32 of the mine and is attached at its upper end to the buoyant section 31.

To prevent accidental discharge of the mine and permit it to be safely handled, it may be equipped with any suitable means. As shown in the form illustrated in Figs. 1 to 3, a locking pin 40 projects from a casing 41 secured to the buoyant body over the lever 8. At its inner end said pin is provided with an enlarged head between which and an end wall of the casing 41 is arranged a coiled spring that acts to withdraw the pin from engagement with the lever 8. A securing pin 42 is normally passed through an aperture in the pin 41 and acts to prevent movement of the latter under the effect of the spring referred to.

In addition to employing the pins 40, 42 as a safety means, the mine is shown as equipped with means adapted to be rendered ineffective only after it has been submerged. The casing 41 in rear of the piston-like head on the pin 40 is filled with a suitable soluble substance, for example sugar, and an inlet 50 to the chamber containing this substance is closed by a readily detachable closure 43.

Prior to placing the mine in the water the closure 43 is removed and the pins 13^a and 42 withdrawn.

In the form of the invention illustrated in Figs. 4 and 5, the hydrostatically controlled connection between the two sections 31, 32 is equipped with equivalent safety devices, which are well known in the art.

While any suitable form of hydrostatic means, generally designated 35 in Figs. 4 and 5 may be employed, Fig. 8 illustrates in detail one form of such a device.

Referring to this figure 70 designates a tubular member which is shown as provided

at one end with an exteriorly threaded section, 70^a, that may be welded or otherwise secured to the body and is engaged with a threaded passage formed in a wall of the mine body which is preferably made somewhat thicker adjacent said passage than at other points. To the end of the section 70^a that projects from the body of the mine is secured a hollow head 71 which as shown is provided with an exterior annular groove 75 or channel to receive the cable that is employed to connect the two sections of the mine. Within the chamber in the head 71 is arranged a plate-like member 72 having oppositely directed sleeve-like projections 71^a, 80 71^b, the former extending into the tubular member 70 and being connected to a firing pin support 73. The inner end of this support normally extends into an opening in a disk 70^b that is screwed into the tubular member 70.

The outer end of the chamber in the head 71 is closed by a plug 71^c which has a centrally positioned opening over which is arranged a cap 71^d provided with an aperture 90 that is normally closed by a readily removable sealing strip 71^e.

A diaphragm 74 is arranged over the outer face of the plate-like member 72, its edge being confined between the body of the head 71 and suitable washers adapted to be adjusted inward by the plug 71^c. A disk or washer 74^a is screwed on the projection 71^b of the plate-like member 72 and acts to retain the diaphragm in substantially the relation shown.

Within the outer end of the cylinder 73 which supports the firing pin is arranged a suitable cartridge 75.

The firing pin 76 is surrounded by a spring 76^a which extends between the head of said pin and an abutment formed in the cylinder 73. A latch 75^b normally engages an enlargement on the stem of the firing pin and extends into the opening in the disk 70^b 110 so that the spring 76^a is held under compression and the firing pin in the retracted position shown.

Between the cylindrical members 70, 73, is arranged a coiled spring 77 the outer end 115 abutting the sleeve-like extension 71^a of the plate member 71 and its inner end bearing against an adjusting nut 70^d portions of which are exposed through slots formed in the member 70.

When the mine is not submerged the parts are retained in the positions shown in Fig. 8 by a block 78 of suitable material, for example, sugar, which will be dissolved when exposed to water. The tension of the spring 125 77 is adjusted so that its expansive action will be counterbalanced by the pressure of water on the diaphragm when the mine is submerged to the desired depth.

If the mine rises, owing to the cable 10 130

being cut, the pressure exerted by the water on the diaphragm will be reduced and the spring 77 will withdraw the inner cylindrical member 72 from the opening in the 5 disk 70^b. As the latch 75^b escapes from the disk it will release the firing pin and the latter will be impelled forward by the spring 76^a to explode the cartridge 75.

The explosion of the cartridge 75 will 10 break the connection at 35 between the two sections of the mine but will not effect explosion of the main explosive charge.

No claim is herein made to the novel features of the particular form of hydrostatic 15 control described as they are claimed in a pending application, filed April 6, 1918, Serial Number 227,083.

It is thought that the operation and advantages of the invention will be apparent 20 from the foregoing description. It will be seen that if the anchor cable is cut or broken so that the lever 8 is released from the pull or strain intended to be exerted by the anchor thereon, or in the embodiment of the 25 invention illustrated in Figs. 4 and 5 the mine is caused to rise above a certain level, the firing pin 76 will be released and the cartridge 75 exploded. This will blow off the outwardly projecting part of the hydro- 30 static device 35, thus destroying that connection between the two parts of the mine and permitting the lower explosive containing section thereof to swing downwardly about the connections 33, 34 and to move 35 entirely away from the upper section. During such separating movement the receptacle 12^a will be broken and as soon as the section of the cable above the cut or break therein has passed from between the contacting 40 rollers the electric circuit will be completed and the mine exploded. As the upper section of the mine will rise but a relatively short distance, before the lower section falls sufficiently to escape from contact 45 with the cable, the explosion will occur at a depth which is close to that at which the cable was cut and therefore assuming that the cutting was effected by a submarine the latter will not have had opportunity 50 to escape from the area affected by the explosion. Such an attachment therefore renders it practically impossible to destroy mine fields by the means that has been commonly employed.

An important feature of the invention is 55 that it does not in any way interfere with the operation of the mine in the ordinary manner. The explosive charge will be detonated by contact with any of the projecting members 4 in the ordinary manner and in addition said charge will be set off if the anchor cable is broken.

By reference to the circuits shown in 60 Figs. 2 and 6 it will be seen that when any one of the contacts 4 is broken, by being

struck by a vessel for example, an electric circuit will be established from the battery, produced by breaking the frangible container 52 in said contact, through the primer charge 60 thus exploding the mine in the 70 ordinary manner. If the cable is cut the explosive charge and its container will be separated from the buoyant casing or section of the mine and while the conductors of the circuit between the contacts 4 and 75 primer 6 are severed, another circuit will be established including the battery formed by the device 12, the primer charge 60 and the contacts 15, 16, the latter operating to close said circuit and explode the primer only 80 after the rollers, 18, 20 are below the cut end of the cable.

Having thus described the invention what is claimed and desired to be secured by Letters Patent is:

1. In a sub-marine mine, the combination of a buoyant casing, a container for an explosive charge normally connected with the buoyant casing, an anchor, connections between the anchor and buoyant casing, and 90 means whereby the explosive charge and buoyant casing will be automatically disengaged and said charge detonated if the connection between the casing and anchor is broken.

2. In a sub-marine mine, the combination of a buoyant casing, a container for an explosive charge normally connected with said casing, means on the casing for detonating said explosive charge, an anchor, connections 100 between the anchor and buoyant casing, and means whereby said explosive charge and buoyant casing may be automatically disconnected and said charge detonated.

3. In a sub-marine mine, the combination 105 of a buoyant casing, a container for an explosive charge, an anchor, a cable connecting the buoyant casing and anchor and extending through the explosive charge container, means whereby the casing and explosive charge container may be automatically disconnected, and means for detonating the explosive charge after it is disconnected from the buoyant casing.

4. In a fixed sub-marine mine the combination 115 of a buoyant casing, a container for an explosive charge, normally connected with said casing, an anchor connected with the casing, means whereby said casing and container may be automatically disconnected if 120 the connection with the anchor is broken, and means for detonating the explosive charge after it has been disengaged from said casing.

5. In a fixed sub-marine mine the combination 125 of a buoyant casing, a container for an explosive charge normally connected with said casing, an anchor for holding the mine in position, means whereby the casing and explosive charge container will be automati- 130

cally disconnected and the latter permitted to move downwardly from the casing, and means for detonating the charge when it is separated from the casing to a certain extent.

6. In a sub-marine mine, the combination of a buoyant casing, a container for an explosive charge normally connected with said casing, means whereby said casing and container may be automatically disconnected, an electric circuit for detonating the explosive charge, and means for rendering said circuit operative when the explosive charge is entirely disconnected from the buoyant 10 casing and the cable carried thereby.

7. In a sub-marine mine, the combination of a buoyant casing, a container for an explosive charge normally connected with said casing, means whereby the casing and container may be automatically disconnected, an anchor, a cable connecting the anchor and buoyant casing, an electric circuit for detonating the explosive charge, and means controlled by the anchor cable for rendering said 20 circuit operative.

8. In a sub-marine mine, the combination of a buoyant casing, a container for an ex-

plosive charge normally connected with said casing, an anchor, a cable connecting the anchor and buoyant cable and extending 30 through the casing containing the explosive charge, means whereby the casing and container may be automatically disconnected, means for detonating the explosive charge, and means for preventing detonation of the 35 explosive charge until the casing and container are entirely separated.

9. In a sub-marine mine, the combination of a buoyant casing, a container for an explosive charge normally connected with said 40 casing, means on the buoyant casing adapted to effect detonation of the explosive charge, an anchor connected with the casing, means whereby the buoyant casing and container will be automatically disconnected when the 45 connection between the casing and anchor is broken, a supplemental detonating device carried by the container, and means for automatically actuating said supplemental device after the casing and container are 50 disconnected.

In testimony whereof I affix my signature.

DMITRY TROUBTSCHANINOFF.
